CONTAINER CAP

George Goebel, Baltimore, Md., assignor to
 Crown Cork & Seal Company, Inc., Baltimore,
 Md., a corporation of New York

Application February 26, 1936, Serial No. 65,885

4 Claims. (Cl. 215—38)

The present invention has as its object to produce container caps of a type which may be readily snapped on and off without use of tools of any kind.

5 This object is attained by the design of cap shown by way of example in the accompanying drawing, and I shall proceed to explain the invention with reference to this specific embodiment.

10 In the drawing:

Figure 1 is an elevation of the new cap as applied to a container.

Figure 2 is a section, considerably enlarged, on the line 2—2 of Figure 1.

15 Figure 3 is an axial section of the cap shell in an initial stage of manufacture.

Figure 4 is an axial section of the completed cap shell, and

Figure 5 is a plan view of the cap.

20 Referring first to Figures 3 to 5, in the manufacture of the cap, I first stamp out or otherwise produce, a shell in the form shown in Figure 3 from suitable sheet metal, such as the usual tin plate. The gauge of the metal will depend to some extent on the size of the cap to be made, lighter gauges being utilized for the smaller caps and heavier gauges for the larger sizes. The shell shown in Figure 3 has a circular top portion 10, which centrally is somewhat inwardly offset 25 as at 11. The cap has a skirt portion which includes a substantially cylindrical band 12 immediately adjoining the top portion 10. From this band the skirt is rather abruptly outwardly flared, the flare including an annular portion 13 substantially normal to the band 12 and an inclined portion 14. The skirt portion is continued into a substantially cylindrical terminal portion 15, which is provided with axially extending corrugations 16.

30 The shell thus constituted is subjected to a bending operation, whereby the marginal portion 15 is bent sharply inwardly from the circumferential bending line 14', the edge 17 taking a circular form and the depth of the corrugations 16' 35 at the edge being somewhat deepened as compared to their original form. In Figures 1, 2 and 4 the inwardly bent marginal portion is designated as 15'.

40 The finished shell 18 has inserted therein a cushion or gasket 19 of suitable material, and this gasket when of sufficiently heavy stock, may be conveniently retained merely by friction with the inner surfaces of band 12.

45 The glass container 20 shown in Figures 1 and 2 has a tubular end portion 20' which defines a

5 mouth. Spaced inwardly from its extremity, the tubular end portion is provided with a circumferential rib 21, which is substantially rectangular in cross section as shown in Figure 2. The top face of the rib is less abruptly inclined than the lower face, the latter forming a shoulder for engagement by the cap. A substantially cylindrical portion 22 exists between the rib 21 and the container lip.

10 The diameter of the circular edge 17 is slightly less than the maximum diameter of rib 21, whereas the diameter of the circumferential bending line 14' is considerably greater than the maximum diameter of the rib. The internal diameter of band 12 is slightly greater than the 15 outside diameter of the portion 22 of the container.

15 The cap may be applied with a direct straight-line movement, but ordinarily one side will first come in contact with the container lip and complete application obtained by a swinging movement. As the edge 17 passes over the rib, it deforms or expands momentarily and then contracts under the shoulder to bring a substantial portion of the corrugated margin under the latter. The proportions are such that this contraction 20 tensions the skirt portion so that the top of the cap is moved toward the container lip and the gasket suitably compressed to effect a seal. The offset in the top portion of the cap lies inside 25 the inner edge of the lip and tends to bend the gasket over the latter to improve the seal. When the cap is fully applied, as shown in Figure 2, band 12 cooperates with the end portion 30 22 of the container to hold the cap centered. In the absence of this provision, the cap could 35 become accidentally tilted, due to the large clearance between the rib and the flare of the skirt, and in such case the seal would be impaired or destroyed.

40 To remove the cap, the thumb is merely placed beneath margin 15' and upward pressure exerted, edge 17 snapping over rib 21 and releasing the cap. The cap may be snapped on and off innumerable times without appreciable deformation.

45 The cap flare and inturned margin act as an infinite number of C clamps. It will be noted that these portions have a very considerable radial extent and in the embodiment shown constitute 50 approximately a quarter of the total diameter of the cap. The relatively great width of margin 15' enables it to flex readily. In the application of the cap, the top surface of the rib or flange 21 has a powerful camming effect on edge 17. When 55

- edge 17 passes under the shoulder, a powerful tensioning effect is exerted on the skirt portion, this effect and the locking effect being enhanced by the abruptness of the shoulder inclination.
- 5 Margin 15' flexes more easily on removal than on application, so that the locking effect as enhanced by the relative abruptness of the lower surface of the rib is overcome on removal with no difficulty.
- 10 The cap may be used in the packaging of various products either in solid or liquid form. The skirt tension is such that an excellent seal is provided, but at the same time the locking provisions are such that the cap is readily manipulated.
- 15 The invention is not limited in embodiment to the specific design herein disclosed. Changes in form and proportions may be made without departure from the invention, and accordingly I do not limit myself except as in the following 20 claims.

I claim:

1. For use with a container having a tubular portion with a mouth at one end thereof, said tubular portion being provided with an external circumferential rib which presents an annular shoulder faced away from the mouth, a metal cap having a top portion and a skirt portion, the free marginal portion of said skirt portion being sharply bent inwardly on a circumferential line 25 to provide a continuous circular edge whose diameter is slightly less than the maximum diameter of said rib, the circumferential line of said bend having a diameter considerably greater than the maximum diameter of said rib, the cap being 30 adapted to be snapped on said tubular portion to engage said edge under said shoulder, the proportions being such that when said edge is engaged under said shoulder said skirt portion is tensioned and draws said top portion toward the 35 extremity of said tubular portion to effect a seal, the skirt portion immediately adjacent said top portion being formed so as to closely embrace the end of said tubular portion and thereby center the cap.
- 40 2. For use with a container having a tubular portion with a mouth at one end thereof, said tubular portion being provided with an external circumferential rib which presents an annular shoulder faced away from the mouth, a metal cap having a top portion and a skirt portion, the free 45 marginal portion of said skirt portion being corrugated and sharply bent inwardly on a circumferential line to provide a continuous circular edge whose diameter is slightly less than the maximum 50 diameter of said rib, the circumferential line of said bend having a diameter considerably greater than the maximum diameter of said rib, the cap being adapted to be snapped on said tubular portion to engage said edge under said shoulder, the proportions being such that when said edge is engaged 55 under said shoulder said skirt portion is tensioned and draws said top portion toward the extremity of said tubular portion to effect a seal.

der, the proportions being such that when said edge is engaged under said shoulder said skirt portion is tensioned and draws said top portion toward the extremity of said tubular portion to effect a seal, the skirt portion immediately adjacent said top portion being formed so as to closely embrace the end of said tubular portion and thereby center the cap.

3. For use with a container having a tubular portion with a mouth at one end thereof, said tubular portion being provided with an external circumferential rib which presents a shoulder faced away from the mouth, said rib being spaced from the mouth, a metal cap having a top portion and a skirt portion, the skirt portion comprising a band immediately adjoining the top portion and formed to closely surround that part of the tubular portion between said rib and mouth whereby to center the cap when it is applied, the skirt portion continuing in a sharp flare from said band up to a circumferential line from which it is bent sharply inwardly to form a circular edge having a diameter slightly less than the maximum diameter of said rib, the circumferential line of bend having a diameter considerably greater than the maximum diameter of said rib, the cap being adapted to be snapped on said tubular portion to engage said edge under said shoulder, the proportions being such that when said edge is engaged under said shoulder said skirt portion is tensioned and draws said top portion toward the extremity of said tubular portion to effect a seal.

4. For use with a container having a tubular portion with a mouth at one end thereof, said tubular portion being provided with an external circumferential rib which presents a shoulder faced away from the mouth, said rib being spaced from the mouth, a metal cap having a top portion and a skirt portion, the skirt portion comprising a band immediately adjoining the top portion and formed to closely surround that part of the tubular portion between said rib and mouth whereby to center the cap when it is applied, the skirt portion continuing in a sharp flare from said band up to a circumferential line from which it is bent sharply inwardly to form a circular edge having a diameter slightly less than the maximum diameter of said rib, the inwardly bent portion being corrugated, the circumferential line of bend having a diameter considerably greater than the maximum diameter of said rib, the cap being adapted to be snapped on said tubular portion to engage said edge under said shoulder, the proportions being such that when said edge is engaged under said shoulder said skirt portion is tensioned and draws said top portion toward the extremity of said tubular portion to effect a seal.

GEORGE GOEBEL.
